DAVID J. L. DAVIS AND GEORGE W. WALLACE, OF NEW YORK, N. Y., ASSIGNEES TO
S. E. COMPANY, OF SAN FRANCISCO, CALIFORNIA, A CORPORATION OF DELAWARE.

APPARATUS FOR DISTILLING OIL SHALES AND THE LIKE.

Application filed September 20, 1922. Serial No. 589,353.

Our invention relates to the heat treatment of oil-shales, by which term we intend to include all solid mineral materials which contain hydrocarbons and yield oil when subjected to heat, either by destructive distillation or by simple distillation, the purpose of said treatment being to obtain oils and by-products therefrom. It consists in a novel apparatus by which the operation can be carried on continuously without it being necessary to heat the chamber or generator externally. We not only provide for the continuity of the operation but make use of direct internal combustion in the shale itself to furnish the required heat.

In an application filed by us of even date herewith, Serial No. 589,352, claiming the novel process, we have described and illustrated the apparatus, which forms the subject matter of this application, as a means for carrying out the process which, broadly stated, consists in progressively feeding the shale upwardly through a closed chamber while drawing or forcing air, with or without an inert gas or steam, downwardly through the chamber and the charge of shale contained therein, the shale being ignited at the top and the air maintaining a zone of combustion in the upper part of the chamber, into and through which the shale is constantly being slowly fed, while the oils and vapors distilled off from the shale as it approaches said zone, filter down through the column of cold shale and are drawn off at the bottom of the closed chamber or generator.

In the accompanying drawings, illustrating a simple form of apparatus embodying our invention,

Fig. 1 is a side elevation of the apparatus, a portion of the chamber wall being broken away.

Fig. 2 is a plan sectional view of the same on line 2-2 of Fig. 3, and

Fig. 3 is a vertical central section through the upper part of the chamber.

In the example illustrated in these views, the closed chamber 1, in which the shale is treated, is supported in a vertical position by columns 2, and consists of a cylindrical section, a central conical section 4, and a curved tapering section 5 leading into the bottom of said conical section the other end of said curved section having its axis horizontal and constituting the feed inlet for

the raw shale. The top of section 3 is surrounded by a trough 6 and the chamber is closed by a cover 7. A down-spout 8 for the spent shale leads down from an opening in the bottom of said trough. On a central shaft 10, driven by the bevel gear drive 11, are carried the scraper arms 12, on the ends of which are blades 13, traveling in the trough 6. From the horizontal end of portion 5 a suitably trapped outlet pipe 14 for the oils leads downward, and to the face of said end is secured the feed casing 15, containing a reciprocating piston 16, or other suitable means for feeding the shale upwardly through the chamber 1. The axis of the casing 15 is somewhat above that of the horizontal end section 5, so that the incoming shale will not interfere with the escape of the oil through the outlet pipe 14. The raw shale is supplied to the casing 15, for example, from a closed bin 18. An inlet 19 is provided through the cover 7 for the air and other gases and a suction blower may be connected to the outlet 21 below the bin 18 to create a partial vacuum in the apparatus to draw the air, etc. downward through the chamber and the pressure in the same be maintained above atmospheric, if desired, instead of using suction and a pressure below atmospheric. The vapors, which are not condensed in their passage through the raw shale in the chamber, are preferably drawn off through said outlet 21, but may be drawn off through the pipe 20, through which the bin 18 is filled, so as to obtain additional contact with the incoming cold shale before they are conducted to final condensing and scrubbing apparatus not shown.

A portion of the non-condensable gaseous products of combustion may be returned to the inlet 19, by suitable pipe connections, not shown, so as to temper or modify the oxidizing action of the incoming air and thereby control the intensity of the combustion. Steam has the same effect and also serves to increase the recovery of ammonium compounds, when the shale contains considerable nitrogenous matter.

While we have shown a conventional reciprocating piston feed for the shale, we contemplate using a modification of the underfeed stoker, of the kind in common use for feeding coal to boiler furnaces, or even, in some cases, an ordinary screw con-

veyor, which may then be arranged in the vertical axis of the generator. It is not essential that the generator be on a perfectly vertical axis, for it may be inclined, if preferred. Other modifications in mechanical detail may be made without departing from the spirit of our invention, as expressed in the following claim:

Having thus described our invention,
10 what we claim is:

Apparatus for the continuous distillation of oil shale by internal combustion, comprising a vertical retort tapered downwardly with its lower end curved into the horizontal, a cover for the top of said retort, a

trough surrounding said top within said cover, revoluble scraper arms, having depending portions traveling in said trough, a gas inlet through said cover, an oil outlet from said curved end, and means to feed the shale into said end, whereby the shale is fed upward into and through a zone of combustion maintained in the top of the retort, the oils being distilled off from the shale below said zone.

In testimony whereof we have hereunto set our hands.

DAVID J. L. DAVIS.
GEORGE W. WALLACE.
